(57) **CLAIM**

The ornamental design for a binocular case, as shown and described.

DESCRIPTION

FIG. 1 is a front, top, left-side perspective view of the binocular case;

FIG. 2 is a front elevational view thereof;

FIG. 3 is a top plan view thereof;

FIG. 4 is a right-side elevational view thereof;

FIG. 5 is a left-side elevational view thereof;

FIG. 6 is a rear elevational view thereof;

FIG. 7 is a bottom plan view thereof; and,

FIG. 8 is a front, top, left-side perspective view thereof in an open state.

The broken lines depict unclaimed parts of the binocular case, and thus form no part of the claimed design.
